[73] Assignee: **Nisca Corporation**, Yamanashi, Japan

CLAIM

[**] Term: 14 Years

The ornamental design for an image processing machine for inputting recording medium into a personal computer, as shown and described.

[21] Appl. No.: 928,192

DESCRIPTION

[22] Filed: Aug. 12, 1992

FIG. 1 is a perspective view of an image processing machine for inputting recording medium into a personal computer showing our new design, the broken line drawings of supporting document trays are for illustrative purposes only and form no part of the claimed design;

[30] Foreign Application Priority Data

FIG. 2 is a rear elevation view of the image inputting machine of the invention;

Feb. 22, 1992 [JP] Japan 4-4673

FIG. 3 is a top plan view thereof;

[52] U.S. Cl. D14/114

FIG. 4 is a front elevation view thereof;

[58] Field of Search 358/400-404;

FIG. 5 is a bottom plan view thereof; and,

361/600, 622, 627-636, 679, 683-687;
D14/114, 116, 113, 124, 299; D18/54-55

FIG. 6 is a right side elevational view thereof, the left side is a mirror image.
